COMBINATION TABLE AND TELEVISION PICTURE PROJECTION UNIT

Max Teuber, Los Angeles, Calif., assignor of one-half to Joseph W. Boak, Los Angeles, Calif.

Application February 18, 1952, Serial No. 18,552

Term of patent 7 years

(Cl. D61—1)

To all whom it may concern:

Be it known that I, Max Teuber, a citizen of the United States, residing at Los Angeles, in the county of Los Angeles and State of California, have invented a new, original, and ornamental Design for a Combination Table and Television Picture Projection Unit, of which the following is a specification, reference being had to the accompanying drawing, forming part thereof.

In the drawing;

Fig. 1 is a perspective view of a combination table and television picture projection unit embodying my new design, showing the top and end doors in open position;

Fig. 2 is an end elevational view taken from the left of Fig. 1;

Fig. 3 is an end elevational view taken from the right of Fig. 1; and

Fig. 4 is a perspective view showing the end and top doors closed and the side leaves extended.

I claim:

The ornamental design for a combination table and television picture projection unit, substantially as shown.

MAX TEUBER.
